(57) **CLAIM**

What is claimed is the ornamental design for a level indicator for telescopic sights, as shown and described.

DESCRIPTION

FIG. 1 is an elevated front perspective view of a level indicator for telescopic sights showing our new design in a closed position.

FIG. 2 is a depressed rear perspective view of the level indicator of FIG. 1.

FIG. 3 is a front elevational view of the level indicator of FIG. 1, the back being a mirror image thereof.

FIG. 4 is a right side elevational view of the level indicator of FIG. 1.

FIG. 5 is a left side elevational view of the level indicator of FIG. 1.

FIG. 6 is a top plan view of the level indicator of FIG. 1.

FIG. 7 is a bottom plan view of the level indicator of FIG. 1.

FIG. 8 is another elevated front perspective view of the level indicator of FIG. 1 showing the level indicator in an open position; and,

FIG. 9 is another elevated front perspective view of the level indicator of FIG. 1 shown in a position of use on a telescopic sight.

The broken dash lines in the form of a telescopic sight in FIG. 9 depict environmental subject matter and form no part of the claimed design. All the other broken dash lines in the figures depict portions of the level indicator for telescopic sights that form no part of the claimed design.
